DESIGN FOR AN ILLUMINABLE SWITCH PLATE

Thomas L. Wheeler, Jr., Columbus, Ohio

Application October 2, 1944, Serial No. 115,559

Term of patent 14 years

(Cl. D26—13)

To all whom it may concern:

Be it known that I, Thomas L. Wheeler, Jr., a citizen of the United States, residing at Columbus, in the county of Franklin and State of Ohio, have invented a new, original, and ornamental Design for Illuminable Switch Plate, of which the following is a specification, reference being had to the accompanying drawings, forming part thereof.

Fig. 1 is a front elevational view of the illuminable switch plate showing my new design;
Fig. 2 is a horizontal cross-sectional view;
Fig. 3 is a rear elevational view; and
Fig. 4 is a vertical central cross-sectional view.

I claim:

The ornamental design for an illuminable switch plate, as shown.
